UNITED STATES PATENT OFFICE.

ELMER A. RICH, JR., OF CHICAGO, ILLINOIS, ASSIGNOR TO THE AMERICAN FOUNDRY EQUIPMENT COMPANY, OF NEW YORK, N. Y., A CORPORATION OF OHIO.

SAND-BLAST MACHINE.

1,377,993.

Specification of Letters Patent. Patented May 10, 1921.

Application filed April 7, 1916. Serial No. 89,532.

To all whom it may concern:

Be it known that I, ELMER A. RICH, Jr., a citizen of the United States, residing at Chicago, in the county of Cook and State 5 of Illinois, have invented a certain new and useful Improvement in Sand-Blast Machines, of which the following is a full, clear, concise, and exact description, reference being had to the accompanying drawings, forming 10 a part of this specification.

My invention relates to sand blast machines by which a blast of sand may be directed against articles, such for example as castings, so as to clean or otherwise treat the 15 same.

Prominent objects of the invention are to provide a simple, practical and effective sand blast machine; to arrange for the easy and ready introduction of the articles to be 20 treated into the machine, also the ready, quick and convenient removal of said articles from the same; to arrange for the economical use of the sand by automatically returning the same after use into position 25 to be used again; to arrange for the effective treatment of the articles within the machine so that such treatment will be efficient and even over all portions of the articles; and to accomplish the foregoing and other desirable 30 results in a simple and expeditious manner.

In the accompanying drawings Figure 1 is a front view of a sand blast machine embodying my present invention;

Fig. 2 is a side elevation of the same; 35 Figs. 3, 4, 5, and 6 are views of details of construction.

In the drawings I show a machine embodying a framework having front side uprights 1-1 and rear side uprights 2-2. 40 Mounted more or less centrally in the frame is a rotary drum 3 which is to receive the articles to be acted upon and also to receive a sand blast which shall act upon said articles when they are in said drum. The drum 45 3 as best shown in Fig. 3, is arranged to rotate about two stationary heads 4-4, one at each end (one only being shown in Fig. 3), which heads 4 are mounted stationarily upon or in the machine so that they fit 50 within the ends 5-5 of said drum 3, thereby permitting the drum to rotate about said heads. The heads 4 are preferably in the form of flat disk-like metallic members provided with laterally extending arms or

brackets 6 and 7 which latter extend lengthwise of bracket members 8-8 and are bolted to the same by bolts 9-9, the members 8 being in turn bolted to horizontally arranged forwardly and rearwardly extending channel members 10-10 secured at their 60 ends to the side uprights 1-1 and 2-2, as shown in Fig. 2. The ends 5-5 of the rotary drum 3 are preferably provided with wear plates 11, each of which conveniently consists of a ring fitted within a circular 65 aperture in the end 5 and having an outwardly extending annular web portion 12 adapted to fit within the inner edge portion of the end 5 immediately surrounding said central aperture therein. Bolts 14 secure the 70 ring 11 to the end 5. Thus these rings 11 fit over the stationary heads 4 and turn on the same so as to permit the drum 3 to have the desired rotary motion relative to said heads. The wear plates may be changed without 75 changing the drum. The ends 5 of the drum 3 are made as best shown in Figs. 1 and 3,—that is, said ends are made with inclined surfaces 15 and 16 (Fig. 3) whereof the surfaces 15 project or incline outwardly from the axial or head portion of the drum and the surfaces 16 extend and incline inwardly from said head portion. The surfaces 15 are situated diagonally across from one another on the drum, and the surfaces 16 are also 80 diagonally opposed to one another. In this way the ends of the drum in effect form sloping surfaces substantially parallel with one another at the ends of the drum, and these surfaces have the effect of moving or throwing 85 the articles, such as castings, located within the drum, back and forth so as to expose them properly to the air blast in such a way as to insure proper and even treatment. When as the drum rotates, the castings are in the upper part of the barrel or drum, they will of course fall to the bottom, and in so doing the inclined ends at the left side of the drum, referring to Fig. 1, will 90 throw said castings or other articles to the right, and so turn them over and over exposing them on all sides to the sand blast. When the drum has revolved 180 degrees from the position shown in Fig. 1, the castings or other articles will be thrown to the 95 left because of the inclination of the right hand side or end of the drum. In this way there is a continual shifting back and forth

of the castings or other articles and a consequent effective treatment by the air blast. The drum is made with perforations 18 in its cylindric wall by which the sand can 5 escape.

The sand blast is directed into the drum 3 by means of nozzles 20 (Figs. 1, 3 and 4). These nozzles pass through the stationary heads so that they continually direct the 10 sand blast into the interior of the drum 3 as the latter is rotated. The nozzles 20 are connected with tubular members 21 having longitudinally extending air passages 22 and parallel ducts or passages 23 for the 15 sand. The nozzles 20 are secured to the end of the members 21 by means of couplings 24 secured to the members 21 by screws 25 and having mixing chambers 26 and small apertures 27 through which the air passes 20 at high pressure. Each member 21 is arranged at an inclination preferably about 45 degrees to the vertical, so that the sand blast is directed at that angle into the drum 3 at each side thereof. Sand boxes 28 are mounted 25 on opposite sides of the machine and provided with apertures 29, into which sand may pass into the sand ducts 23. Valves 30 control the apertures 29 and are in turn controlled by levers or handles 31, Figs. 4 and 5. Each lever 31 is pivoted at 32 so that by swinging the handle 31 the valve portion 30 opens and closes the outlet aperture 29. The air ducts 22 are connected with air inlet pipes 33 which run to the 35 opposite ends of a water separator 34 for separating the water from the air, said pipe 33 being provided with controlling valves 35 for the different air ducts. The water separator 34 may be of any suitable or preferred construction. Air under pressure is admitted to it through an air inlet pipe 37, the air entering through this pipe 37 and circulating through the separator 34 and then passing out the opposite ends of the 40 same into the pipes 33 and thence into the air blast nozzles.

Sand is supplied to the sand boxes 28 in a continuous manner from the discharge from the rotary drum 3, there being a continuous circulation of said air kept up into the drum 3 by the sand blast nozzles from the boxes 28 and then into the drum again and so on continually. This is brought about by an endless conveyer 40 having 50 buckets 41, said conveyer traveling over pulleys 42 and 43 at the bottom of the machine and 44 at the top of the same. The buckets 41 in passing in the direction indicated by the arrow in Fig. 1 from the pulley 42 to 55 the pulley 43 gather up the sand which is on the floor of the machine and elevate it until the pulley 44 at the top of the machine is reached, in going around which the buckets 41 empty the sand which they are 60 carrying. The sand which the buckets 41

gather from the floor of the device is deposited there by means of a platform forming a slide or chute 45 (Fig. 2) which is located below the drum 3 and inclines forwardly so that sand coming from the drum 70 slides down said slide or chute 45 into the space 46 where it is gathered by the buckets 41. The sand discharged by the buckets 41 in passing over the upper pulley 44 falls into a hopper 47 striking the sides of the 75 same, (Fig. 1), and thence through a spout 48 attached thereto upon a screen 49 located in an aperture in the top 50 of a sand box 51 (Fig. 6). Within this box 51 there are two downwardly and forwardly inclined slides 52 which extend outwardly from under the screen 49 to the side edges of the machine and terminate in extensions 53 on the tops of the sand boxes 28, whereby sand 80 discharged from the buckets 41 and into the hopper 47 passes through the screen 49 and on to the slides 52 and thence downwardly upon the latter into the sand boxes 28. From these latter it is discharged 85 through the nozzles 20 into the drum 3 as previously described. The upper pulley 41 is driven so as to drive the sand conveyer by means of a shaft 54, gear connected with a main driving shaft 55 carrying a pulley 56 and a friction clutch 57 operated by a hand lever 58.

The rotary drum 3 is preferably driven by driving mechanism consisting of driving rolls 59 located underneath the drum 3 and having driving surfaces in contact with 100 annular driven rims 60 formed or provided at the opposite sides of said drum. The driving rolls 59 are mounted upon a shaft 61 which is driven by a sprocket chain 62 in turn driven by a sprocket wheel 63 on the 105 driving shaft 55.

The drum 3 is provided with a door 65 which may be held in position by means of straps 66 whose ends are engaged by cleats 68 and whose opposite ends pass over projections 69 having pins 70 whereby the door may be opened by disengaging it from the projections 69 by removing the pins 70 and also disengaging the straps 66 from the cleats 68. This permits castings or other 110 articles to be treated to be inserted into the interior of the drum.

As an arrangement for conveniently handling the door 65 I provide mechanism by which said door may be mechanically engaged and lifted and held in suspense in an elevated position, while castings are inserted into or removed from the barrel, after which the door may be lowered back to its closed position. This mechanism comprises a 120 swinging frame conveniently constructed of a straight upper bar 86 (Fig. 1), and a lower inclined bar 87, both pivoted to one of the side upright members 1 as at 88 and 89, respectively, said bars being connected to 125 130

gether at their outer or swinging ends so that together they form a swinging frame which may be swung to one side or the other of the upright 2 to which it is pivoted. In 5 Fig. 1 I show said frame in solid lines swung to the left and in dotted lines swung to the right. In the left hand or solid line position, the swinging or free end of the frame is in front of the central or middle part of 10 the door 65, as shown in Fig. 1. Said swinging frame carries a lever 90 which is pivotally mounted on the free end of the frame, being pivoted thereto by a pivot 91 (Fig. 2). One end of said lever 90 is short and has a 15 hook 92, whereas the other end is long and adapted to be grasped by the hand. Thus when the frame with the lever 90 is swung to a position in front of the door 65, as shown in Fig. 1, the long or outer end of the handle 20 may be swung down so as to lift the short end, the door 65 being provided with a lug or eyelet 93 which will be engaged by the hook or end 92 so that when the lever is operated in this way the door 65 will be raised. 25 In order to hold the door in an elevated position a pin 94 may be inserted into one of a series of holes 95 so that the long end of the lever 90 may be pushed down below said pin and the latter will hold the lever 30 depressed and the door elevated. The holes 95 are provided in two side members 96 which are secured to the free end of the swinging frame and arranged crosswise of said end, as shown in Figs. 1 and 2. By such 35 arrangement the door may be elevated and lowered as desired to permit the insertion and removal of castings without having to remove the door from the drum. When the adjustment of the door is completed the 40 swinging frame may be swung away from in front of the door and drum and off to one side, as shown by dotted lines in Fig. 1.

In order to remove said articles when through their treatment the door 65 is opened 45 and then the drum turned so that the opening where the door fitted is underneath. This allows the articles to fall out. In order to catch them as they drop, a truck (not shown) is placed in the space 71 below the 50 drum. To permit the truck to be placed in this space the platform 45 is made so that it can be lowered not only to get it out of such space but also so that it will form a floor for the truck. A convenient arrangement is to 55 have said platform pivoted at 72 so that it may be swung down to a horizontal position. A counterweight 73 for balancing the platform 45 is mounted on a rod or lever 74 secured to the pivotal shaft 72 on the 60 opposite side to the platform 45. Furthermore, a swinging door 75 is mounted on hinges 76 so that it may normally be in position to close the space above the platform 45 when the latter is in its inclined position as 65 shown in Fig. 2. In this position said door

is locked by a locking device 77. When however, it is desired to use the truck to receive the articles from the rotary drum, the door 75 is swung outwardly on the hinges 76, thereby getting it out of the way so that the 70 truck can be introduced into the space 71.

The rotary drum 3 is preferably inclosed in vertical walls which are supported by the side members 1 and 2 and at the front of the machine a vertically sliding door 80 is 75 provided by which access can be had to the drum. This door is carried by a cable 81 extending upwardly around a pulley 82 and thence over a pulley 83 and downwardly, and provided at its ends with a counterweight 84. 80 It will be understood that changes and modifications may be made without departing from the spirit of the invention.

What I claim is:

1. The combination of a rotary drum provided with apertures for the escape of sand, a frame supporting said drum, and an inclined platform located below said drum and arranged to convey sand downwardly from said drum, said platform being hinged near 90 the floor so that when swung down into a horizontal position it will form a support for a truck.

2. The combination of a rotary drum provided with apertures for the escape of sand, 95 a frame supporting said drum, and an inclined platform located below said drum and arranged to convey sand downwardly from said drum, said platform being hinged near the floor so that when swung down into a 100 horizontal position it will form a support for a truck, and a counterweight and arms for counterbalancing said platform.

3. The combination of a rotary drum provided with apertures for the escape of sand, 105 a frame supporting said drum, and an inclined platform located below said drum and arranged to convey sand downwardly from said drum, said platform being hinged so as to permit it to be swung down into a horizontal position to form a support for a truck, a counterweight and arms for counter-balancing said platform, and swinging doors arranged to close the space above said inclined platform.

4. The combination of a rotary drum provided with apertures for the escape of sand, 120 said drum having ends which are inclined to the axis of the drum except at their central portions which are perpendicular to said axis and are provided with central openings, and a pair of heads arranged axially of the drum at the opposite ends of the same, said heads having platelike members which close said apertures and also serve as bearings for the drum, and sand discharge nozzles extending through said platelike members and arranged to discharge sand into the interior of said drum, the ends of said drum being provided with detachably mounted 125 130

wear rings fitting in the apertures or openings in said drum ends and also fitting over and rotating upon said platelike members.

5. The combination with the frame having upwardly extending corner members and horizontal cross pieces of a rotary drum arranged within the frame, rotary shafts below the drum and provided with means for rotating the drum, a single inclined member 10 arranged below the drum and extending in a continuous downward inclination from side to side of the drum, and a single traveling conveyer arranged at one side of the frame and having its lower end located adjacent 15 to the lower end of said inclined member, said inclined member being hinged at one edge to the frame near the bottom of the same, whereby said member may be swung from its inclined position downwardly to a 20 horizontal position at or near the bottom of said frame.

6. The combination with the rotary drum provided with apertures for the escape of sand, of sand blast nozzles at the opposite 25 ends of said drum, a single traveling conveyer, means for conveying the sand from said drum to said conveyer and means for distributing the sand from said conveyer to the nozzles at the opposite ends of the drum.

30 7. The combination with the rotary drum provided with apertures for the escape of sand, of sand blast nozzles at the opposite ends of said drum, a single traveling conveyer, means for conveying the sand from 35 said drum to said conveyer and means for distributing the sand from said conveyer to the nozzles at the opposite ends of the drum, said last mentioned means comprising a pair of chutes, one extending to the nozzle at one 40 end of the drum and the other extending to the nozzle at the other end of the drum.

8. The combination with the rotary drum provided with apertures for the escape of sand, of sand blast nozzles at the opposite 45 ends of said drum, a single traveling conveyer, means for conveying the sand from said drum to said conveyer and means for distributing the sand from said conveyer to the nozzles at the opposite ends of

the drum, said last mentioned means comprising a pair of chutes, one extending to the nozzle at one end of the drum and the other extending to the nozzle at the other end of the drum, said chutes having their upper ends adjacent one another and a single sand discharge member arranged to receive sand from said traveling conveyer and discharge the same upon the upper ends of said chutes.

9. The combination of a rotary horizontally disposed apertured drum, a single inclined member located below said drum for receiving and conveying all of the sand therefrom to one side of the machine, a vertically arranged endless conveyer having its lower portion located at the lower end of said inclined member, an outlet for sand at the upper end of said traveling conveyer, sand discharge nozzles at the opposite ends of said drum and means for receiving sand from said outlet and distributing the same to said nozzles.

10. The combination of a rotary horizontally disposed apertured drum, a single inclined member located below said drum for receiving and conveying all of the sand therefrom to one side of the machine, a vertically arranged endless conveyer having its lower portion located at the lower end of said inclined member, an outlet for sand at the upper end of said traveling conveyer, said discharge nozzles at the opposite ends of said drum and means for receiving sand from said outlet and distributing the same to said nozzles, said last mentioned means including a box 51 containing two chutes 52 having their upper ends united and their lower ends separated and extending to the opposite sides of the frame to points above the sand nozzles and a screen 49 located below the discharge member for discharging sand from the traveling conveyer.

In witness whereof, I hereunto subscribe my name this 21st day of March, A. D., 1916.

ELMER A. RICH, JR.

Witness:

A. LYDA JONES.
